CLAIM

The ornamental design for a tire sidewall, as shown and described.

DESCRIPTION

FIG. 1 is a perspective view of a tire sidewall showing my design;

FIG. 2 is a front elevation view of the tire sidewall of FIG. 1;

FIG. 3 is a rear elevation view of the tire sidewall of FIG. 1;

FIG. 4 is a side elevation view of the tire sidewall of FIG. 1;

FIG. 5 is a side elevation view taken from the opposite side of that shown in FIG. 4; and,

FIG. 6 is a detailed view taken from FIG. 1.

The broken line disclosure in the drawings depicts environmental subject matter forming no part of the claimed design.

1 Claim, 6 Drawing Sheets
